UNITED STATES PATENT OFFICE.

ONESIME E. MICHAUD, OF ST. LOUIS, MISSOURI.

ATTACHMENT FOR SHOTGUNS.

No. 927,572.

Specification of Letters Patent.

Patented July 13, 1909.

Application filed March 15, 1909. Serial No. 483,486.

To all whom it may concern:

Be it known that I, ONESIME E. MICHAUD, a citizen of the United States, and a resident of the city of St. Louis and State of Missouri, have invented a new and useful Improvement in Attachments for Shotguns, of which the following is a specification.

My invention relates to shotguns and more particularly to single-barreled guns.

It has for its principal objects to provide for the attachment of a removable extension or choke muzzle section, to secure stability of attachment, and to prevent accidental displacement.

The invention consists in the parts and in the arrangements and combinations of parts hereinafter described and claimed.

In the accompanying drawing forming part of this specification, and wherein like symbols refer to like parts wherever they occur, Figure 1 is an inverted plan view of the forward end portion of a single-barreled gun with a removable muzzle section embodying my invention attached thereto; Fig. 2 is a similar view with the locking lever in opened position; Fig. 3 is an inverted plan view of the forward end portion of the gun barrel showing the notch for coöoperating with the locking lever; Fig. 4 is a side elevation of the parts shown in Figs. 1 and 2; Fig. 5 is a longitudinal vertical section; Fig. 6 is a fragmentary top view of the coupling portions of the gun barrel and muzzle section detached; and Fig. 7 is a vertical section showing a modification of the locking lever and retaining ring.

The gun is a single-barreled gun of any ordinary type. On the forward end of the barrel 1 at the top thereof is a stud or sight 2. In the bottom of the gun barrel is a rounded notch or depression 3.

The removable muzzle section or extension 4 is bored to constitute a continuation of the bore of the gun barrel proper. It may be choke-bored or otherwise bored to suit any particular purpose. The muzzle section has an enlargement or bell portion 5 at its rear end which is counterbored so as to fit over the forward end of the gun barrel 1 and also to provide an annular shoulder 6 adapted to fit squarely against the end of said gun barrel. A notch or slot 7 is provided in the edge of the counterbored portion at the top thereof so as to receive the gun sight 2 or a specially provided lug or stud, if desired.

Mounted on a horizontal pindle in lugs 8 on the bottom of the muzzle section is a locking lever 9. This lever has a circular enlargement 10 at its pivot end which is arranged to project through a slot 11 in the bottom of said muzzle section. This circular enlargement 10 projects into the notch 3 in the bottom of the gun barrel 1, and it is adapted to fit snugly therein when the muzzle section is placed on the gun barrel. A portion of the circular enlargement of the locking lever is cut away, as at 12, to clear the outer face of the gun barrel 1 when the lever is moved to turn the circular portion from the notch 3 in attaching and detaching the muzzle section. The forward end of the lever is adapted to fit under an annular offset portion or flange 13 on a ring 14 which is loosely mounted on the muzzle section next to the bell portion. A portion of the annular flange 13 is cut away or slotted as at 15 to permit the end of the locking lever to pass therethrough; and the outer face of said portion 13 is preferably knurled to facilitate turning the ring. A fixed retaining ring 16 or other suitable device may be provided to prevent the ring from moving endwise on the muzzle section. The locking lever is provided with a curved lateral extension 17 near its forward end, and on the end of this extension is an outwardly offset forwardly projecting lip or extension 18 which terminates on a line with the end of the main portion of the lever. The main portion of the lever is rigid, but said curved lateral extension 17 is a spring.

In order to permit the locking lever and its curved lateral extension to lie flush with the outer face of the muzzle member, angularly disposed grooves or depressions 19, 20 are provided therein. When the muzzle section is mounted on the end of the gun barrel, the ring 14 is turned to register with the groove 19 and the locking lever 9 is then swung over and pressed into the groove against the tension of the spring of its curved lateral extension 17 whose end extension 18 rests on the outer face of the annular flange 13 of said ring 14. After the lever is depressed through the slot 15 the ring is turned to move its annular portion over the end of said lever. A continued rotation of the ring will bring its slotted portion 15 under the projecting lip 18 on the spring arm or extension 17 of the lever whereupon said lip 18 will snap into said

slotted portion and lock the ring against rotation. When it is desired to detach the muzzle section the end 18 of the spring arm 17 is lifted from the notch in the ring 14 5 and said ring is turned until its notch is in line with the main portion of the lever. The lever may then be raised and moved far enough to release the circular pivot portion from the notch in the gun barrel. The muzzle section may then be slipped from the barrel.

In order to facilitate the removal of the end portion 18 of the lever spring extension 17 from the slot in locking ring flange 13, 15 it is preferable to bevel one side of said slot, as at 21, so that, by forcibly turning said ring, the end portion 18 of the spring extension will ride up onto the outer face of said ring flange 13. The tension of the spring 20 extension 17 is sufficient, however, to hold the ring against accidental movement.

In Fig. 7 the locking ring 14^a is provided with an internal groove which is adapted to coöperate with a small rib 22 on the end of 25 the locking lever. In this case, it is unnecessary to provide a retaining ring or other device as the rib on the lever will be sufficient to hold the ring against endwise movement when the parts are in locked 30 position.

Obviously, my device admits of considerable modification without departing from my invention. Therefore, I do not wish to be limited to the specific construction and 35 arrangement shown and described.

What I claim as my invention and desire to secure by Letters Patent is:

1. A single-barreled shotgun having an attaching portion on its forward end, a removable muzzle section having an end portion adapted to fit squarely against the end of the gun and a sleeve portion adapted to fit around the end of said gun, a locking lever on said muzzle section having a counterpart portion adapted to interlock with the attaching portion on the forward end of said gun, a ring revolvably mounted on said muzzle section, said ring having an annular portion adapted to lock said lever in position, and means for releasably holding said revolute ring in locking position.

2. A single-barreled gun having an attaching portion on its forward end, a removable muzzle section having an end portion adapted to fit squarely against the end of the gun and a sleeve portion adapted to fit around the end of said gun, a locking lever on said muzzle section having a counterpart portion adapted to interlock with the attaching portion on the forward end of said gun, a ring revolvably mounted on said muz-

zle section, said ring having an annular portion arranged to overlap the end of said locking lever and also having a slot in its annular portion to permit the end of the lever to pass therethrough, and a spring extension on said lever arranged to engage the slotted portion of said revolute ring to releasably hold said parts in locked position.

3. A single-barreled gun having a projection on the top face of its forward end and a notch in its bottom face, a removable muzzle section having an end portion adapted to fit squarely against the end of the gun and a sleeve portion adapted to fit around the end of said gun, said sleeve portion having a slot in its upper edge portion adapted to receive the projection on the top face of the gun, a locking lever on the bottom side of said muzzle section having a counterpart portion adapted to fit in the notch in the bottom face of the gun, a ring revolvably mounted on said muzzle section, said ring having an annular portion arranged to overlap the end of said locking lever and also having a slot in its annular portion to permit the end of the lever to pass therethrough, and a spring extension on said lever arranged to engage the slotted portion of said revolute ring to releasably hold said parts in locked position.

4. A single-barreled gun having a projection on the top face of its forward end and a notch in its bottom face, a removable muzzle section having an end portion adapted to fit squarely against the end of the gun and a sleeve portion adapted to fit around the end of said gun, said sleeve portion having a slot in its upper edge portion adapted to receive the projection on the top face of the gun, a locking lever on the bottom side of said muzzle section having a counterpart portion adapted to fit in the notch in the bottom face of the gun, a ring revolvably mounted on said muzzle section, said ring having an annular portion arranged to overlap the end of said locking lever and also having a slot in its annular portion to permit the end of the lever to pass therethrough, and a curved lateral spring extension on said lever, said extension having a forwardly projecting end portion adapted to fit in the slot in said revolute ring to releasably hold said parts in locked position.

In testimony whereof I have signed my name to this specification in the presence of two subscribing witnesses this 13th day of March, 1900, at St. Louis, Missouri.

ONESIME E. MICHAUD.
